UNITED STATES PATENT OFFICE

2,118,699

VIBRATOR AND HOLDER THEREFOR

Edward M. Chappell, Chicago, Ill., assignor to
 Bally Manufacturing Company, Chicago, Ill., a
 corporation of Illinois

Application February 18, 1936, Serial No. 64,535

2 Claims. (CL. 128—41)

The invention relates to a vibrator used in massaging treatments and more particularly to holder means for conveniently carrying the vibrator in operative position on the part of a person's torso, or the like, sought to be treated.

In locating the vibrator on the part to be treated it is sometimes convenient to support the vibrator in a belt or carrying band, which may be fastened about the user's body, or parts thereof, with the vibrator thus held in operative position at the desired place.

The invention aims particularly to provide an improved, simple belt or band for this purpose, said band having means for ready and quick attachment to headed studs mounted on the vibrator body. The means mentioned is, of course, also quickly detachable from the vibrator.

Sometimes it is also desirable to hang the vibrator in a supported position from a wall hook or the like, and the invention therefore also contemplates the provision of a simple ball device attachable to or removable from the vibrator as occasion requires.

The main object of the invention is to provide improved holder means for a vibrator of the type mentioned to facilitate, and make convenient, its use.

Another object is to provide a carrier band for the vibrator including means for quickly attaching to and detaching same from the vibrator.

Also it is an object to provide a ball device for hanging the vibrator when the belt is used in some conditions of service.

Other objects will become apparent to those skilled in this art as the disclosure is more fully made.

The vibrator to be illustrated is of the type having a cylindrical body, carrying at one end a mounting for the vibration applicator. Said body rigidly carries on its outer surface a number of headed studs in spaced relation, which serve as attaching buttons to receive the ends of the carrier band or belt by means of simple button holes formed in the band. Said band includes a buckle so that it may be secured around a person's body in a manner holding the vibration applicator in the desired spot to be treated. One end of the vibrator body carries oppositely disposed sockets to receive detachably, the legs of a spring wire bail so that when desired the vibrator may be suspended from a wall hook.

The improved structure is shown in the accompanying sheet of drawings, wherein:

Figure 1 is a general perspective view of the vibrator with the ends of the band attached

thereto and with the carrying bail also shown in position;

Figure 2 is another general perspective view showing the vibrator strapped in position on a user's torso, the bail not being used in this instance;

Figure 3 is an enlarged perspective assembly view of the vibrator connected with the belt and hung by the bail from a wall hook;

Figure 4 is a rear end view of the vibrator showing the ends of the belt attached thereto; and,

Figure 5 is a detail, elevational view of the bail, per se.

The vibrator is of that class embodying a cylindrical body 10 provided with a boss 11 at one end to carry a vibration applicator 12. Adjacent the applicator end of the body there are provided four equidistantly spaced, rigid headed studs 13, all preferably lying in the same or substantially the same plane.

The carrier band comprises two relatively wide belt portions 14 formed of suitable material such as leather or fabric as desired, each portion having an end formed with a pair of button holes 15 to fit over a pair of the studs 13 on the vibrator. One opposite end of a belt portion carries a suitable buckle 16 cooperable with the opposite end of the other portion in an obvious manner to permit the belt or band to be strapped around a user's body as shown in Figure 2 to hold the vibrator in operative position.

The other end of the vibrator is formed with diametrically opposed sockets 17 to receive the ends of a U-shaped spring metal ball 18 in the manner shown in Figures 1 and 3, whereby the vibrator may be hung from a wall hook 19 when desired. By this means the user when he has the vibrator strapped on with the unit at his back may lean against the vibrator thereby creating pressure which sometimes is desirable.

It can now be seen that an improved means has been provided for holding a vibrator of the class described in operative position on the user with auxiliary cooperating means provided to hang the vibrator from a wall hook. This holding means, of course, is simple and effective and achieves the desirable objects heretofore recited.

It is the intention to cover all changes and modifications of the example of the improved structure shown for purposes of the disclosure which do not in material respects constitute departures from the spirit and scope of the invention as hereinafter claimed.

What is claimed is:

1. In a vibrator of the class having an elong-

gated body including a cylindrical end portion carrying two pairs of radial studs in spaced relation, the combination with the studs of a pair of relatively wide bands having complementarily paired cooperative means at one end respectively for securement to the respective pairs of studs whereby to hold the said band ends in an axial direction relative to the axis of the vibrator body and respectively in wrapping engagement with said body, the other ends of said bands including a separable fastener whereby the band may be secured around a user's torso in a manner to hold the vibrator body with its axis normal to the user's torso.

15   2. In a vibrator of the class described having

an elongated body including a cylindrical end portion carrying two pairs of radial studs in spaced relation and all lying in substantially a common plane cutting through said body, the combination with the studs of a pair of relatively wide bands having complementarily spaced pairs of holes formed respectively in adjacent band ends for securement of an end of each band to each pair of studs in a manner to hold the said attaching ends of the bands in an axial direction relative to the vibrator body and closely in wrapping engagement with said body, and the other ends of said bands including separable fastener means to secure said other ends together.

EDWARD M. CHAPPELL. 15
